(74) Attorney, Agent, or Firm — Burr & Forman LLP

(57) **CLAIM**

The ornamental design for a blower, as shown and described.

DESCRIPTION

FIG. 1 is a front, left side perspective view of our new design for a blower;

FIG. 2 is a front elevation view thereof;

FIG. 3 is a rear elevation view thereof;

FIG. 4 is a top plan view thereof;

FIG. 5 is a bottom plan view thereof;

FIG. 6 is a left side elevation view thereof; and,

FIG. 7 is a right side elevation view thereof.

The broken lines in FIGS. 1-7 depict portions of the blower that form no part of the claimed design.

1 Claim, 7 Drawing Sheets(56)
